UNITED STATES PATENT OFFICE.

GEORGE W. SHANK, OF MONCURE, NORTH CAROLINA.

REVERSING VALVE-GEAR FOR ENGINES.

1,013,076.

Specification of Letters Patent. Patented Dec. 26, 1911.

Application filed September 15, 1910. Serial No. 582,239.

To all whom it may concern:

Be it known that I, GEORGE W. SHANK, a citizen of the United States, residing at Moncure, in the county of Chatham and State of North Carolina, have invented new and useful Improvements in Reversing Valve-Gears for Engines, of which the following is a specification.

This invention relates to engine valve gears of the reversing type.

The invention has for one of its objects to improve and simplify the construction and operation of mechanism of this character so as to be comparatively simple and inexpensive to manufacture, reliable and efficient in use and composed of comparatively few parts.

Another object of the invention is the employment of a novel arrangement of operating eccentrics and an adjustable rocker whereby the point of cut-off can be varied, the engine reversed and a quick movement imparted to the valve as the same covers or uncovers the admission and exhaust ports so that wire drawing of the steam and back pressure will be reduced to a minimum.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a side view of the valve gear set in position for forward driving. Fig. 2 is a similar view, showing the valve gear in its other extreme position. Fig. 3 is a diagrammatic view of the operating cams and rocker that imparts movement to the valve rod. Fig. 4 is an edge view of the rocker actuating cams.

Similar reference characters are employed to designate corresponding parts throughout the several views.

Referring to the drawing A designates the bed of an engine which has at one end a cylinder 1 provided with a steam chest 2, to and from which steam passes through the inlet and exhaust pipes 3 and 4 respectively, there being an ordinary slide valve (not shown) in the steam chest for controlling the admission and exhaust of the operating fluid. The stem 5 of the valve reciprocates through the stuffing box 6 and the forward

end slides in a bearing 7 on the bed of the engine.

The crank shaft 8 is provided with a pair of cams 9 and 10, which impart movement to the slide valve. These cams co-act with each other for oscillating a rocker or link 11, which is pivoted on a stud 12 carried by a block 13, the said block sliding in a guide or slot 14 arranged on the bed A concentrically to the crank shaft 8 of the engine. The block is connected by a link 15 with a bell crank reversing lever 16 fulcrumed at 17 on the engine bed. The link or rocker 11 has an arcuate slot 18 in which slides a block 19 that carries a pivot stud which extends into an opening 21 in the forward end of the valve rod 5. In order to reduce friction between the rocker and cams 9 and 10 the rocker is provided with rollers 22 and 23 that ride respectively on the cams 9 and 10.

The cams are similar as to size and configuration and each has its peripheral surface formed with two oppositely disposed concentric parts α and α' and two eccentric portions b and b' , the portions α and α' being of different radii. The cams are arranged on the shaft so that the concentric portions of greater radii are approximately diametrically opposite, although the axes x and x' and y and y' of the two eccentrics are displaced from each other approximately thirty degrees. By angularly displacing the eccentrics in this manner the rocker can have a relatively fixed axis on which to oscillate, while at the same time the rollers 22 and 23 will maintain their engagement with the cams. The eccentric portions of the cams cause the oscillation of the rocker and hence the sliding movement of the valve, while the concentric portions of the cams maintain the rocker idle and the slide valve stationary during the major portion of the exhaust and admission period.

The eccentric portions of the cam cause the slide valve to move quickly so that wire drawing of the incoming steam will be reduced to a minimum. The effective throw of the rocker can be changed by manipulating the lever 16 for varying the point of cut-off and furthermore the engine can be stopped or reversed by the same lever.

From the foregoing description, taken in connection with the accompanying drawing, the advantages of the construction and of the method of operation will be readily ap-

parent to those skilled in the art to which the invention appertains, and while I have described the principle of operation of the invention, together with the apparatus which I now consider to be the best embodiment thereof, I desire to have it understood that the apparatus shown is merely illustrative, and that such changes may be made when desired as are within the scope of the 10 claims appended hereto.

Having thus described the invention what is claimed as new, is:—

1. In a reversing valve gear, the combination of a rotating shaft, a pair of similar 15 cams on the shaft angularly displaced one hundred and eighty degrees, a stationary arcuate guide concentric with the shaft, a rocker, means slidable in the guide and connected with the center of the rocker, a device for shifting the said means and rocker, devices located at opposite sides of the rocking axis of the rocker and respectively engaging the cams continuously, a reciprocating valve rod, and means for hingedly and 20 slidably connecting the valve rod with the rocker.

2. In a reversing valve gear, the combination of a rotating shaft, a pair of similar 30 cams on the shaft angularly displaced one hundred and eighty degrees, a stationary arcuate guide concentric with the shaft, a rocker, means slidable in the guide and connected with the center of the rocker, a de-

vice for shifting the said means and rocker, devices located at opposite sides of the rocking axis of the rocker and respectively engaging the cams continuously, a reciprocating valve rod, said rocker having an arcuate slot curved reversely to the said arcuate guide, a reciprocating valve rod, and means 40 slidable in the slot of the rocker for connecting the valve rod with the latter.

3. In a reversing valve gear, the combination of a pair of cams arranged on a common axis and each having oppositely-disposed concentric portions of different radii and intermediate eccentric portions, the portions of greater radii being disposed at opposite sides of the center of rotation, a stationary guideway concentric with the axis 50 of the cams, a member slidable in the guideway, a rocker centrally pivoted on the member, rollers mounted on the rocker at opposite sides of the rocking axis thereof for contacting respectively with the cams continuously, a slide valve rod, means for slidably mounting the rod and preventing movement transverse to the axis thereof, and means for hingedly and slidably connecting the rod with the rocker.

In testimony whereof, I affix my signature in presence of two witnesses.

GEORGE W. SHANK.
